Term of patent 7 years

To all whom it may concern:

Be it known that we, Glen A. Mengle and George C. Noblit, citizens of the United States, residing at Brockway, in the county of Jefferson and State of Pennsylvania, have invented a new, original, and ornamental Design for a Bottle Cap, of which the following is a specification, reference being had to the accompanying drawing, forming a part thereof.

In the drawing:

Fig. 1 is a top plan view of the bottle cap, showing our new design;

Fig. 2 is a side elevational view thereof;

Fig. 3 is a bottom plan view; and

Fig. 4 is a fragmentary perspective view showing a portion of the periphery of the bottle cap on an enlarged scale.

The surface shading in Fig. 1 represents high lights on the top of the cap and forms no part of the design. The showing of some of the panels in Fig. 2 light and others dark is shading only; all of the panels are of the same color.

We claim:

The ornamental design for a bottle cap, as shown and described.
